Key, of Sowell, in the County of Middlesex and State of Massachusetts, have originated and designed an improvement in a pattern for Carpets or other fabrics, of which the following is a full, clear and exact description, reference being had to the accompanying drawings making part of this specification.

This improvement consists in substituting the bands of small lines 1, 2, 3, the light sprig work 4, 4, and 5, 5, the bars 6, 6, and the dotted ground 7, for the figures and grounds occupying a corresponding position in Design designated as "Application No. 5" for which Letters Patent were granted June 16th 1863, and bearing the Patent Office number 1774.

The remainder of the design is copied from the one before mentioned.

The colors employed for the different portions of the design, may be varied to suit the taste and wish of the manufacturer.
